UNITED STATES PATENT OFFICE.

MICHAEL WATERS, OF SIOUX CITY, IOWA.

CHANNEL-FORMING DEVICE.

Application filed December 5, 1927. Serial No. 237,627.

My invention relates to channel forming devices of the type illustrated in my co-pending application, Serial Number 181,435, filed Apr. 6, 1927.

5 An object of the present invention is to provide an arrangement in which the cutting device overcomes the resistance of the sand bar, with greater facility than the cutter of the prior device.

10 More specifically, it is my object to provide a channel forming device, in which the cutters are carried forwardly of a swinging crane similar to that illustrated in my co-pending application but in which every portion 15 of that frame in a lateral direction is positioned behind the cutters so that the frame will not jam against the edge of the channel being cut.

A further object is to provide a channel forming device of the type shown in my co-pending application which eliminates the necessity of drive chains.

20 A still further object is to provide a simple, durable, and inexpensive arrangement, embodying the features above set forth.

With these and other objects in view, my invention consists in the construction, arrangement and combination of the various parts of my device, whereby the objects contemplated are attained, as hereinafter more 30 fully set forth, pointed out in my claim, and illustrated in the accompanying drawings, in which:

Fig. 1 is a plan view of the forward extremity of a boat, equipped with the device of my invention.

Fig. 2 is a sectional view, taken on the line 2-2 of Fig. 1.

Fig. 3 is a sectional view taken on the line 40 3-3 of Fig. 1.

Fig. 4 is a sectional view taken on the line 4-4 of Fig. 1.

The present invention involves the same general principles of construction as the device shown in my co-pending application and therefore only features of novelty are shown in the drawings attached hereto.

It will be understood that a barge 10 is provided with a capstan feed arrangement, similar to that shown in my co-pending application and a source of motive power, which drives the drive chain 11, corresponding to the drive chains shown in my co-pending application.

55 A transverse shaft 12, which serves the double purpose of supporting the swinging,

cutting device and of carrying power to the cutters thereof corresponds to the shaft for the same purpose shown in my co-pending application.

The shaft 12 is mounted in four bearings 60 13, which are shown in Fig. 4 and which are secured to the forward end of the boat 10 and provided with removable bearing caps 14.

The swinging frame, which supports the 65 cutter, includes two longitudinal side bars 15, two longitudinal, intermediate bars 16, and an upper and lower transverse bar 17 and 18, respectively. The bars 17 and 18 secure the bars 15 and 16 in spaced relation 70 and the entire structure is suitably braced by diagonal braces 19.

The ends of the bars 15 and 16 project beyond the bar 17 and these projecting ends are provided with bearings 18' and 19', respectively, which inclose the shaft 12 so as to 75 swingingly mount the frame upon the boat 10. Removable caps 20 allow the frame to be disconnected from the shaft 12.

The frame is lifted and supported by means 80 of cables 21, secured to the bar 18 and extending through forks 22 of the swinging booms 23, corresponding to the same elements in my co-pending application. The booms 23 are provided at their upper ends with bearings 85 24 and removable bearing caps 25, by means of which the booms are pivotally and removably mounted upon the shaft 12.

The cutting elements comprise two sets of 90 closely spaced cutters 26, which are designed similar to drill bits, being provided with the pointed noses 27. The cutting elements may be removed from their shafts.

The cutters 26 and 26^a are carried upon 95 spaced parallel shafts 28 and 28^a, which are mounted in bearings 29 and 30, on the bars 18 and 17, respectively. The bearings 29 and 30 are provided with movable caps 31 and 32, respectively, whereby the shafts 28 may be readily removed. On the shaft 12 are secured a plurality of spaced, bevelled gears 33 and 33^a, which mesh with bevelled gears 34 and 34^a, respectively, on the shafts 28 and 28^a, respectively.

The chain 11 drives a sprocket 35 on the 105 shaft 12.

The cutters 26 are provided with right-hand threads and the cutters 26^a with left-hand threads or vice versa, whereby any side thrust tended to be produced by the rotation 110 of the cutters in the silt of a river bed will be neutralized. The number of right-

hand threaded cutters equals the number of lefthand threaded cutters and they are preferably positioned with all of the cutters of one type on one side of the center of the machine and all of the cutters of the other type on the other side of the center.

The bevel gears 33 are reversed, relative to the bevel gears 33^a, whereby the rotation in the shafts 28 may be reversed relative to 10 the shafts 28^a, and the cutters thereby caused to revolve all of them, in a forward direction. By balancing the bevel gears against each other, end thrust upon the shaft 12 is neutralized, and no provision for end thrust 15 need be made in the bearings 13.

The cutters 26 and 26^a are all spaced with their peripheries closely adjacent each other and the side bars 15 are positioned at their outer ends entirely behind the outer cutters. 20 Thus, as the machine progress forwardly, fed by mechanism, shown in my co-pending application, the revolving cutters will eat their way into the silt of the river bed somewhat as indicated in Fig. 2, the current of the water 25 serving to remove the layer of silt above the cutter which is not actually removed by the cutter, and the channel thus being formed, being the full width of the frame so that the latter will not scrape at any point against 30 the silt of the river bed.

The action of the cutters upon the silt is substantially the same with the exception of the above noted improvements, as in my co-pending application, the cutters serving to 35 undermine the bed of silt and the current of the river carrying the latter away.

Some changes may be made in the construc-

tion and arrangement of the parts of my invention without departing from the real spirit and purpose of my invention, and it is 40 my intention to cover by my claim, any modified form of structure or use of mechanical equivalents, which may be reasonably included within their scope.

I claim as my invention:

In a channel forming machine, a floating structure, a driven shaft carried by said floating structure beyond one end thereof, a cutter frame swingingly mounted on said shaft comprising longitudinal bars and transverse bars secured to and connecting said longitudinal bars, the longitudinal bars projecting beyond one of said transverse bars and being provided with bearings, journaled upon said shaft, a plurality of bevel gears upon said shaft arranged in opposed sets, a plurality of spaced parallel cutter shafts arranged at right angles to the driven shaft, a plurality of bearings secured to said transverse bars, bearing caps secured to said bearings, the cutter shafts being journaled in said last mentioned bearings and removable upon removal of said bearing caps, a plurality of bevel gears upon said cutter shafts meshing with the bevel gears on the driven shaft and a plurality of helical cutters on the cutter shafts, the cutter shafts being positioned in vertical planes parallel to the longitudinal axis of the machine.

Signed this 26th day of November, 1927, 70
